UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed July 22, 1925. Serial No. 45,204

This invention relates to improvements in ribbon mechanisms of typewriting machines, and more particularly to means for automatically shifting the ribbon when the carriage reaches a predetermined zone of its travel.

In typing data on insurance policies, the name of the insured party is intended to appear on the face of the policy without an address, and both name and address are required to be carbon-copied on a record-sheet.

Provision is made in the present invention of a simple cam-piece adjustably mounted on a carriage-rod for engagement with a roller on the upper end of a pawl, which engages an arm fast on the usual ribbon switch-shaft, so as to operate the ribbon-shift mechanism. A feature of the invention is a simple means for latching the automatic ribbon-shifting device in inoperative position at will; this means including a cross-arm rotatably mounted on said switch-shaft and arranged for swinging said roller out of engagement with said cam-piece; a latch holding said roller inoperative.

Other features and advantages will hereinafter appear.

In the accompanying drawings,

Figure 1 is a fragmentary front perspective view of the present improvements applied to an Underwood typewriter. The ribbon is shown in its normal position.

Figure 2 is a fragmentary end view of the actuating parts of the automatic ribbon-shifting mechanism of Figure 1 in position for shifting the ribbon from its normal inked band to the uninked band.

Figure 3 is a fragmentary view of the actuating parts of the automatic ribbon-shifting mechanism latched in an inoperative position.

Figure 4 is a fragmentary perspective view of another form the present invention may take, arranged on the Underwood typewriter. The ribbon is shown in its normal position.

Figure 5 is a fragmentary end view of the device shown in Figure 4, with the actuating parts of the ribbon-shifting mechanism in position for rendering the ribbon vibrator silent.

A platen 10 is revolubly mounted in the carriage 11 of an Underwood typewriting machine 12. A type-bar 13 vibrates a universal bar 14 held on a frame 15. An actuator 16, having vertical slots 17 and 18 arranged for engaging actuating pins 19 and 20 fastened

in a lever 21, is slidably mounted on a bracket 22 fastened on the frame 15. A vibrator 23 carrying a ribbon 24 having an inked or black band 24^b and an uninked or white band 24^r is fastened to the outer end of the lever 21. A link 25 is pivotally connected at one end to the actuator 16, and at the other end to a rocking arm 26 on a switch-shaft 27, the latter carrying at its forward end a switch or cross-arm 28 having keys 29 and 30 corresponding to the bands 24^b and 24^r. By depression of either key 29 or 30 and the consequent rotation of shaft 27, the corresponding band of the ribbon is brought into use by causing its associated slot in the actuator 16 to engage with the proper pin in the lever 21. The above-described ribbon-shift mechanism may be substantially the same as that of the Underwood standard typewriter.

To effect the shifting of the ribbon 24 from one band to the other automatically, a cam-piece 35 may be fastened by a screw 36 to a brace 37, which is adjustably mounted on a rod 38 of the carriage frame 11. A roller 40 is carried on a pin 41 fast in a swinging pawl 42, which is pivoted on a stud 43 in a switch-shaft bracket 44 above the switch-shaft 27. The bracket is mounted on the frame of the typewriter 12 by means not shown. A pin 45 in an arm 46, the latter being fastened on switch-shaft 27 by means of a hub 27^a so as to revolve with the shaft, may be engaged by the lower end 47 of pawl 42, thereby causing the switch-shaft 27 to be rotated a small amount clockwise and the ribbon 24 to be shifted by movement of the roller 40 counterclockwise while engaged by the cam-piece 35 upon movement of the carriage 11 to the left.

A small tensile spring 48 fastened to a pin 49 in bracket 44 and the pawl 42 will hold the roller 40 in normal upright position above the stud 43. To render the automatic ribbon-shifting mechanism inoperative at will for any desired period of time, a cross-arm 50, revolubly mounted on switch-shaft 27, carries a pin 53 arranged to engage the pawl 42 above its pivot 43. By pushing the pawl to the right brings the roller 40 into inoperative position where it cannot engage with the cam-piece 35. The cross-arm 50 may be latched to hold the roller in inoperative position by means of a leaf-spring 55 provided with round detents 56 in its outer end arranged to engage in small holes 57 in the bracket 44. The leaf-spring 55 thus holds the cross-arm securely.

latched against the resultant pull of the spring 48, but can be unlatched by light pressure of a finger.

Clockwise movement of the cross-arm 50 is limited by a pin 58 fast in the right end 52 of the cross-arm engaging the downwardly-extending piece 59 of the bracket 44, and movement in the opposite direction is arrested by the right end 52 coming up against an integral cast-portion 60 of the main frame of the typewriting machine 12.

In Figure 1 key 29 is shown held in depressed condition by spring 31 fastened to a pin 31^a in a bracket 34 on the frame of machine 12, which bracket is provided with an open-ended slot 33 in which engages a pin 32 mounted in cross-arm 28. In this condition black letters will be printed on a work-sheet in the machine 12, as indicated by the letter X on the ribbon 24. When the cam-piece 35 moves to the left and engages the roller 40, the uninked or white field of the ribbon will be presented to the types. The white band provides a protective shield and prevents marking on the work-piece, as might occur with the bare type.

The foregoing mechanism may also be used to control the fields of a bichrome ribbon.

In Figures 4 and 5 is shown another form 30 of my invention which may be used in making stencils. A roller 140 is mounted on a pin 141 fast in a T-shaped arm 142 held fast on a sleeve 143 fitting loosely around switch-shaft 27 between brackets 34 and 44. The arm 142 is formed with a bend or loop, so that its lower end, which engages the sleeve 143, may be positioned on the forward side of the bracket 44, and its upper end, to which is fastened the pin 141, may come on the inner side of bracket 44. An upwardly-extending arm 145 is fastened on the sleeve 143 near its forward end adjacent the bracket 34. An upwardly-extending arm 146, pivoted about a pin 147 fast in the lower left-hand corner of the bracket 34, may have a right angle rearward bend just above the top of bracket 34 and an upward bend at a point a short distance to the rear of the arm 145. The upper end portion 148 of the arm 146 may terminate in a ball 149 for easy engagement with an operative's finger and may carry a pin 150 to which is attached one end of a spring 151, the other end of the spring being fastened to the upper end of the arm 145 to prevent the sleeve 143 from turning clockwise around the switch-shaft 27.

An open slot 153 having a flared outer end is provided in arm 146 at a point substantially opposite the slot 33 in bracket 34. The lower side of the flared outer end of slot 153 is arranged to come substantially opposite the pin 32 fast in the cross-arm 28. When the cam-piece 35 is moved to the left and engages the roller 140 and swings it, the sleeve 143 and arm 146 counterclockwise a small amount, the

pin 32 is caused to move upwardly into the rear of the slot 153 (see Figure 5). The cross-arm 28 in which pin 32 is held is rotated a small amount clockwise and turns the switch-shaft 27 on which it is mounted 70 enough to shift the actuator 16 to stencil or silent position. When the cam-piece 35 is disengaged from the roller 140, the ribbon-shifting mechanism is returned to normal position by the pull of a spring 152 fastened to bracket 34 and arm 146, disengaging the latter from pin 32, and immediately thereafter the spring 31 pulling the pin 32 and cross-arm 28 down against the lower side of slot 33, thereby rotating switch-shaft 27 back to normal position. 80

It can be readily seen that the cam-piece 35 may be made as long as necessary and may be fastened by two or more screws 36, if required, which may be arranged to engage the 85 rod 38 to hold thereon the brace 37 against lateral movement. Also the cam-piece 35 may be replaced by a longer or a shorter one of a set, to change the non-printing period of the ribbon. 90

Variations may be resorted to within the scope of the invention, and portions of the improvements may be used without others.

Having thus described my invention, I claim:

1. In a typewriting machine, the combination with a ribbon-shift mechanism for a ribbon having an inked band and an uninked band, said mechanism being normally manually controllable from the front of the machine through the medium of a rockable switch-shaft extending longitudinally of the machine, of means for automatically shifting the ribbon when the carriage reaches a predetermined zone of its travel, said means including a single cam-piece mounted on a front carriage rod of said machine, a swinging pawl, an arm fast on the switch-shaft of said ribbon-shift mechanism arranged to be engaged by said pawl, said pawl being engageable with said cam-piece as the latter moves leftwardly, whereby said shaft is rotated clockwise to bring said uninked band to printing position, and a spring for returning said switch-shaft to initial position to render the inked band effective after the carriage moves beyond said zone. 110

2. In a typewriting machine, the combination with a ribbon-shift mechanism for a ribbon having an inked band and an uninked band, of means for automatically shifting the ribbon when the carriage reaches a predetermined zone of its travel, said means including a brace slidably mounted on a front carriage rod of said machine, a single cam-piece fastened to said brace, a swinging pawl pivoted on the inner switch-shaft bracket of said ribbon-shift mechanism, a roller carried by said pawl arranged for operative engagement with said cam-piece as the latter moves 120 125 130

- leftwardly, an arm fast to the switch-shaft of said ribbon-shift mechanism, a pin on said arm arranged to be engaged by said pawl, whereby said shaft is rotated to render said uninked band effective at the printing point, and a spring for returning the switch-shaft to position for rendering the inked band effective after the carriage travels beyond said zone. 10
3. In a typewriting machine, the combination with a ribbon-shift mechanism for a ribbon having an inked band and an uninked band, said mechanism including a rockable switch-shaft extending longitudinally of the machine and supported near its rearward end by an inner bracket depending from the frame of the machine, of means for automatically shifting the ribbon when the carriage reaches a predetermined zone of its travel, said means including a single cam-piece adjustably mounted on a front carriage rod of said machine, a swinging pawl pivoted on the inner switch-shaft bracket of said ribbon-shift mechanism, said pawl arranged to engage with said cam-piece as the latter travels leftwardly, an arm fast on the switch-shaft of said mechanism arranged to be engaged by the lower end of said pawl, whereby said shaft is rotated clockwise, and a spring arranged to return said shaft to normal position when said cam-piece moving leftwardly passes out of engagement with said pawl. 20
4. In a typewriting machine, the combination with a ribbon-shift mechanism for a ribbon having an inked band and an uninked band, said mechanism including a rockable switch-shaft extending longitudinally of the machine and supported near its rearward end by an inner bracket depending from the frame of the machine, of means for automatically shifting the ribbon when the carriage reaches a predetermined zone of its travel, said means including a cam-piece adjustably mounted on the carriage of said machine, a swinging pawl pivoted on the inner switch-shaft bracket of said ribbon-shift mechanism, said pawl arranged to be operatively engaged by said cam-piece as the latter moves leftwardly, a connection between said pawl and the switch-shaft of said mechanism whereby movement of said pawl counterclockwise rotates said shaft clockwise, and means for rendering said pawl inoperable by said cam-piece. 30
5. In a typewriting machine, the combination with a ribbon-shift mechanism for a ribbon having an inked band and an uninked band, of means for automatically shifting the ribbon when the carriage reaches a predetermined zone of its travel, said means including a cam-piece adjustably mounted on the carriage of said machine, a pawl pivoted on the inner switch-shaft bracket of said ribbon-shift mechanism, a roller mounted on said pawl arranged to be operatively en-
- gaged by said cam-piece as the latter moves leftwardly, a connection between said pawl and the switch-shaft of said mechanism whereby movement of said pawl counterclockwise rotates said shaft clockwise, and a cross-arm loosely mounted on said switch-shaft arranged for engagement with said pawl, whereby said roller may be moved, at will, out of the path of said cam-piece. 70
6. In a typewriting machine, the combination with a ribbon-shift mechanism for a ribbon having an inked band and an uninked band, of means for automatically shifting the ribbon when the carriage reaches a predetermined zone of its travel, said means including a cam-piece adjustably mounted on the carriage of said machine, a pawl pivoted on the inner switch-shaft bracket of said ribbon-shift mechanism, a roller mounted on said pawl arranged to be operatively engaged by said cam-piece as the latter moves leftwardly, a connection between said pawl and the switch-shaft of said mechanism whereby movement of said pawl counterclockwise rotates said shaft clockwise, a cross-arm loosely mounted on said switch-shaft arranged for moving, at will, said roller out of the path of said cam-piece, and a spring latch for said cross-arm whereby said roller may be maintained in such inoperable position. 80
7. In a typewriting machine, the combination with a ribbon-shift mechanism for a ribbon having an inked band and an uninked band, of a cam-piece mounted on the carriage of said machine, a swinging pawl mounted on the inner switch-shaft bracket of said ribbon-shift mechanism, an arm fast on said switch-shaft, a roller carried on the upper end of said pawl arranged to be engaged by said cam-piece upon movement leftwardly of the latter, whereby the lower end of said pawl engages said arm and moves it and said switch-shaft clockwise to operate said ribbon-shift mechanism, to render said uninked band effective at the printing point, a cross-arm device loosely mounted on said shaft arranged to engage said pawl and move, at will, said pawl out of position for engagement with said cam-piece, and a latch for said cross-arm, whereby said roller may be latched in inoperative position. 90
8. In a typewriting machine, the combination with a ribbon-shift mechanism for a ribbon having an inked band and an uninked band, of a cam-piece mounted on the carriage of said machine, a swinging pawl mounted on the inner bracket of the switch-shaft of said ribbon-shift mechanism, an arm fast on said switch-shaft, a roller carried on the upper end of said pawl arranged to be engaged by said cam-piece upon movement leftwardly of the latter, whereby the lower end of said pawl engages said arm and moves it and said switch-shaft clockwise to operate said ribbon-shift mechanism, to render said uninked band 100
- 105
- 110
- 115
- 120
- 125
- 130

effective at the printing point, a cross-arm device loosely mounted on said shaft arranged to move said roller out of position for engagement with said cam-piece, a latch for said cross-arm for holding it in position to keep said roller inoperative, and means, including a pin in the lower portion of said cross-arm arranged to engage the downwardly-extending element of said switch-shaft bracket and the right-hand end of said cross-arm arranged to engage a portion of the frame of said machine for arresting the clockwise and counter-clockwise movements, respectively, of said cross-arm.

9. In a typewriting machine, the combination with a ribbon-shaft mechanism for a ribbon having an inked band and an uninked band, of a cam-piece adjustably mounted on the front carriage rod of said machine, a bracket for supporting the inner end of the switch-shaft of said ribbon-shift mechanism, a swinging pawl pivoted on said bracket, a roller carried by said pawl on its upper end, a spring attached to said pawl and to said bracket arranged to hold said roller normally in position for operative engagement with said cam-piece as it moves leftwardly, an arm-piece fast on said switch-shaft arranged to be swung clockwise by engagement with the lower end of said pawl to render said uninked band effective at the printing point, a cross-arm loosely mounted on said shaft arranged for engagement with said pawl to swing said roller clockwise, against the pull of said spring, out of position for engagement with said cam-piece, means for limiting the throw of said cross-arm in each direction, and a latch for holding said cross-arm in position at the end of its throw in either direction.

10. In a typewriting machine, the combination with ribbon-mechanism and a ribbon-shifting switch for selectively rendering the ribbon effective or ineffective to print, said switch including a rock-shaft extending longitudinally of the machine, of a single cam borne by the carriage, connections between said cam and said rock-shaft, said connections including an element in the path of said cam so as to be engaged and actuated thereby to render the ribbon ineffective to print as the carriage reaches a predetermined zone of its letter-feeding travel, and a spring for restoring said switch to position to render said ribbon effective to print, after the cam moves beyond said zone.

11. In a typewriting machine, the combination with ribbon-mechanism and a ribbon-shifting switch for selectively rendering the ribbon effective or ineffective to print, said switch including a rock-shaft extending longitudinally of the machine, of a single cam borne by the carriage, connections between said cam and said rock-shaft, said connections including an element in the path of said cam so as to be engaged and actuated there-

by to render the ribbon ineffective to print as the carriage reaches a predetermined zone of its letter-feeding travel, and a spring for restoring said switch to position to render said ribbon effective to print, after the cam moves beyond said zone, said cam being replaceable by another cam of a set, to change the non-printing period of the ribbon.

12. In a typewriting machine having a carriage, the combination with a ribbon-shift mechanism, the ribbon having bands of different characteristics, said mechanism being normally manually controllable from the front of the machine through the medium of a rockable switch-shaft extending longitudinally of the machine, of means for automatically shifting the ribbon when the carriage reaches a predetermined zone of its travel, said means including a cam-piece mounted at the forward part of the carriage so as to be readily visible and accessible from the front of the machine, and means operated by said cam-piece and connected to said switch-shaft for rocking the latter to bring another of said bands into operative position.

13. In a typewriting machine having a carriage, the combination with a ribbon-shift mechanism, the ribbon having bands of different characteristics, said mechanism being normally manually controllable from the front of the machine through the medium of a rockable switch-shaft extending longitudinally of the machine, of means for automatically shifting the ribbon when the carriage reaches a predetermined zone of its travel, said means including a cam-piece mounted at the forward part of the carriage so as to be readily visible and accessible from the front of the machine, means operated by said cam-piece and connected to said switch-shaft for rocking the latter to bring another of said bands into operative position.

14. In a typewriting machine having a carriage, the combination with a ribbon-shift mechanism, the ribbon having bands of different characteristics, said mechanism being normally manually controllable from the front of the machine through the medium of a rockable switch-shaft extending longitudinally of the machine, of means for automatically shifting the ribbon when the carriage reaches a predetermined zone of its travel, said means including a cam-piece mounted at the forward part of the carriage so as to be readily visible and accessible from the front of the machine, means operated by said cam-piece and connected to said switch-shaft for rocking the latter to bring another of said bands into operative position, and means for rendering said last-mentioned means inoperative by said cam-piece.
